REMOVABLE HANDBAG COVER

Harry E. Rosenberg, Brooklyn, N. Y.

Application February 21, 1935, Serial No. 7,497

7 Claims. (Cl. 150—28)

This invention relates to devices such as handbags, and has reference to improvements in the construction thereof, and particularly to covers for handbags.

5 One object of the invention is to provide a device of the character described having improved means for mounting a pocket element or cover; also improved means associated with a framed handbag for mounting a cover therefor.

10 Heretofore, covers, such as removable, washable, or reversible covers have been provided for foundation bags of the wholly flexible type, but it was unknown to provide such a cover for a framed bag because of the unusual difficulties involved in matters of construction, neatness, compactness, style and ease and convenience in operation and use. For example, it is necessary to consider that such frames are stiff and occupy 15 considerable space and must be adapted for snug continuous interengagement in closed position. Further, it is much more difficult to easily and conveniently attach a supporting means for a cover to the flexible body of a bag than to the 20 metallic frame thereof, and a connection to the flexible body of a framed bag would cause undue stress on the bag because of the nonyielding character of the frame members. At the same time, the snap sound which occurs in closing a 25 framed handbag, due to impact of the frames against each other, is considered in the art as a highly desirable feature because of a certain appeal produced in the mind of the purchasing public. By my invention, all of the above mentioned difficulties are met and the desirable features retained.

30 Another object of the invention is the provision of a device of the type mentioned having relatively few and simple parts, and which is inexpensive to manufacture and assemble, can be easily and conveniently used and manipulated by the ordinary purchaser, is neat and continuously uniformly retained and durable, reliable and efficient.

35 45 Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the 50 several views.

In the drawing:

Figure 1 is a view in side elevation showing a device embodying the invention.

Fig. 2 is a view in end elevation.

Fig. 3 is a top plan view thereof.

Fig. 4 is a view in end elevation with parts in section along the line 4—4 of Fig. 1.

Fig. 5 is a view in side elevation of a foundation bag embodying the invention, and showing in dot dash lines elements removably associated 10 therewith.

Fig. 6 is a horizontal sectional view taken on line 6—6 of Fig. 5.

Fig. 7 is an isometric view of the cover in detached position.

Fig. 8 is a sectional view taken on the line 15 8—8 of Fig. 7.

Figs. 9 and 10 are views of end and top rod elements respectively.

Fig. 11 shows a fragmentary vertical sectional 20 view taken on lines 11—11 of Fig. 5.

The advantages of the invention as here outlined are best realized when all of its features and instrumentalities are combined in one and the same structure, but, useful devices may be 25 produced embodying less than the whole.

It will be obvious to those skilled in the art to which the invention appertains, that the same may be incorporated in several different constructions. The accompanying drawing, therefore, is submitted merely as showing the preferred 30 exemplification of the invention.

Referring in detail to the drawing, 10 denotes a device embodying the invention. The same may include a foundation bag 11, and a cover 12 therefor. The foundation bag 11 may comprise a flexible bag 13 having an opening and frame channel members 14 of U-shape and hingedly interconnected at 15a for movement toward and away from each other to close and open the 40 bag 13. Each frame member 14 may include a top section 15 and end sections or arms 16 preferably of the so called regular or downwardly opening type, clamped on the edges of the bag opening. As thus far described, the bag 11 may 45 be conventional in construction, arrangement and operation.

The cover 12 may consist of any suitable material, washable or otherwise, and having desirably different appearances or colors inside and 50 out to produce different effects if the cover is reversed. Said cover may be variously constructed and arranged as the invention relates primarily to supporting means therefor, and may include a bag or pocket 17 as of flexible material 55

having an opening adapted to register and being substantially coextensive with the opening of the foundation bag 11. Disposed marginally along the opening of the cover are female or 5 tubular elements or devices which may be in the nature of loops or clips adapted to removably engage around suitable male elements herein-after described. The female elements may be integral or not with respect to the cover. Preferably, I provide tube forming hems such as 18 and 19, formed as by lines of stitching 20. The hems 18 may extend along the top of the cover substantially from end to end thereof, and each may be open at its opposite ends 21. The hems 15 19 may each extend upright along an end of the cover, and may each be open at its upper and lower ends 23. Otherwise the hems 18 and 19 may be closed therealong. It will be noted that adjacent ends 21, 23 of the hems lie at an upper 20 end corner of the cover and form an upright angle with each other, and the hems 19 may be arranged to lie within the confines of the cover; in other words, with the end walls 24 of the cover disposed at the outside of the hems 19. Along 25 the upper edge of each end wall 24, I may provide an elastic transverse strip 25 connected thereto as at 26 and adapted to contract the lower cover portion snugly around the foundation bag, so that the upper free edges of said end 30 walls will be relatively taut and hence comparatively inconspicuous in open and closed positions of the device 10.

To removably mount the cover on the foundation bag, various elements having male and female 35 male interengagement may be provided, with any one of the elements being on the cover and the other on the bag. An element, or both of them, may be pliable, flexible or resilient, or they may be rigid as herein particularly described. The 40 said elements are desirably arranged not to increase to any material degree the thickness of the handbag, and yet to provide substantially continuous interengagement. For engaging the tubular hem portions 18, 19, the companion elements 45 may be engaged therein telescopically or axially as by a lacing or rod. If the tubular hem portions be resilient and longitudinally split, or if the stitching 20 be regarded as a releasable fastening or interlacing, the tubular portions may 50 engage with their companion elements by a transverse relative movement.

Preferably I use the following arrangement and construction for neatness, reliability, attractiveness in appearance, and ease of operation. 55 Each frame member 14 has its top portion 15 provided with a plurality of longitudinally spaced fastening elements 27, desirably lying in the plane of the frame member. Likewise each side or arm portion 16 is provided with a plurality of 60 longitudinally spaced fastening elements 28, 29, preferably lying in the plane of the frame member. Any suitable type of fastening elements may be employed, preferably such as may be directly engageable by suitable rods, such as 30, 65 31 hereinafter specifically described. For this reason the fastening elements are desirably female in character to receive ends or other portions of the rods. A particularly cheap and effective arrangement is obtained by using elements 70 27 and 28 which consist of rings to provide eyes or ears. The lower fastener elements 29 are preferably sockets closed at their lower ends to limit axial motion of their coating rods. The different fastened elements 27, 28 and 29 are 75 secured to the back of the channel frame, or in

any other manner not to interfere with the clamping of the channel frame on the bag 13. Hence the fastener elements project from the frame member, and in the case of the regular channel shown, the direction of projection is 5 outward while with an inverted channel, the direction may be inward, except as the fastener elements may also be regarded as secured to a flange of the channel.

The fastener elements 27 constitute a pair, and the elements 28, 29 constitute a pair for each side of the frame member. Since the elements 27, 28 are located near a top corner of the frame member, an element 27 with adjacent element 28 may cooperate to form a pair and may constitute a one piece structure connected to the frame member. Thus by interconnecting elements 27, 28 at 32, they may form a corner piece for the frame member. The said elements 27, 28 may lie at an angle to each other as shown. The lower 20 elements 29 open toward and in alinement with their companion elements 28, and lie in proximity to but somewhat above the hinge points 15a.

The rod 30 may be cylindrical and provided 25 with means to prevent removal of the rod after the same has been passed through the pair of elements 29. In that case, the rod 30 may have ends projecting in opposite directions from said elements. The means referred to may comprise 30 a fixed head 33 at one end of the rod and a head 34 threadedly removably connected to the opposite end of the rod at 35.

A rod 31 may be provided for each pair of fastening elements 28, 29, each rod 31 being cylindrical and smooth walled throughout, and adapted to have one end seated in socket 29, and its opposite end retained or slightly projecting from element 28.

The assembly of the fastening means will now 40 be described. The rods 31 are passed downward through the ears 28 with their lower ends resting in the sockets 29. Then the rod 30 is passed through the ears 27, and the head 34 connected thereto at 35. The heads 33 and 34 now occupy 45 the angular spaces between the fastener elements 27 and 28, with the head axially overlying the ears 28 and being thus in abutment with the upper ends of the rods 31 to prevent axial movement of the latter. Thus the heads 33, 34 not 50 only serve to prevent removal of the rod 30, but also disengagement of the rods 31 from elements 28 and 29.

It will thus be seen that I have provided an arrangement whereby different parts are secured 55 in place with the aid of only one removable securing means 34, and that I accomplish this by a novel and simple interraction of parts.

The manner of assembling the device 10 will now be described. The foundation bag 11 is inserted into the cover 12. The rods 31 are then inserted in position and caused to pass through the tubular hems 19, each of which registers with its pair of elements 28, 29 and lies between these elements. The rod 30 is next inserted and caused 65 to pass through the tubular hem 18 which registers with the elements 27 and lies in the space therebetween. Upon securing the heads 34 on the rods 30, the assembly is complete. The sockets 29 may be concealed, if desired, by the end walls 70 24 of the cover, with the elastic drawing the end walls snugly against the sockets, to avoid the appearance of too much metal. The device 10 may now be opened and closed in the usual manner. The heads 33, 34 of the adjacent frames 14 may 75

lie in substantial abutment with each other, if desired, and the channel frames may directly contact each other to avoid undue pressure on the adjacent cover material. The cover may wholly 5 conceal the frame members 14, but metal will be visible at 27, 28, 33, 34. The hem portions overlie the channel frames therearound, so that the foundation bag is completely concealed, and a wholly neat, uniform appearance is obtained 10 when the bag 10 is opened. It will be understood that closure means of any suitable type may be secured to the channel members 14, at the backs thereof, and the rods 30 of the frames 14 may lie sufficiently spaced from each other and from the 15 backs of the channel to afford clearance for the cover material and for the like angle plates such as 36, 37, that may carry interengaging portions, not shown. The rods 30 may resiliently laterally press or pinch the cover hems 18 against the 20 plates 36, 37 to prevent longitudinal creeping of the hems along the rods 30, so that wrinkling is avoided. The lower part of the bag 13 may bulge at its ends at 38 to fill out the rectangular shaped cover.

25 The cover 12 may be regarded as permanently as well as removably mounted on frames as shown without using any bag such as 13. Likewise, though with less advantage, the cover may be mounted on a bag 13 without using any frame 30 members such as 14. The bag 11 in itself may be directly used with the parts 30, 31, as ornamentation.

It will be appreciated that various changes and modifications may be made in the device as shown in the drawing, and that the same is submitted in an illustrative and not in a limiting sense, the scope of the invention being defined in the following claims.

I claim:

40 1. A device including a foundation bag having an opening, frame members having top and leg portions connected to the bag along the opening and movable toward and away from each other to close and open the bag, a cover for the bag, and elongated elements extending along the top and leg portions of the individual frame members, each of the portions having end projecting ears, said elements being engaged with the cover and having engagement in said projecting ears for mounting the cover.

45 2. A device including a foundation bag having an opening, frame members having top and leg portions connected to the bag along the opening and movable toward and away from each other to close and open the bag, a cover for the bag, and elongated rod elements extending along the top and leg portions, each of the latter having alined upstanding end sockets, each rod element mounted in a pair of the sockets and overlying its frame member in the plane thereof, and the cover having marginal tubular portions between the sockets with the elements passing through the tubular portions.

50 3. A device including a foundation bag, a cover therefor, said bag and cover having registering openings providing adjoining edges at an angle to each other at each side of the opening, the cover having spaced tubular portions along each of the adjoining edges, and different means for removably engaging in the tubular portions to

mount the cover on the foundation bag, one of said means cooperating with the other means to prevent release of the latter.

4. A device including a foundation bag having an opening, U-shaped channel frame elements 5 clamped on the edges of the bag walls along said opening with the bag walls directly downwardly depending therefrom, said channel members being movable toward and away from each other to open and close the bag, a cover for receiving the bag, said cover having an opening in register with the bag opening and having the marginal portions at each side of the opening thereof provided with a top and upright end tubular hem portions, each of said portions being open at opposite ends, different rods removably passing through the individual tubular portions, each channel element having a plurality of upstanding alined ears connected to the back thereof at the top of the element, each channel element 10 having a plurality of projecting extending alined portions connected to the back of each arm thereof, the upper of said projecting portions being an ear and the lower a closed ended socket 15 facing the said ear, the different ears and projecting portions lying in the plane of the channel member, the ears being located in proximity to the angles between the top of a channel member and the arms thereof, one rod extending through the ears at the top of the channel member and 20 having at its opposite ends a fixed head and a removable head, others of the rods having lower ends seated in the sockets and upper ends extending through the ears alined with the sockets and being in abutment with the adjacent heads. 25

5. A handbag cover having a pocket having an opening along the top and partially down the ends thereof, said pocket being otherwise closed, said pocket having tubular hems extending along the top and ends at opposite sides of the cover 40 relative to said opening, said hems being each open at the upper end corners of the pocket, a foundation bag for the cover, U-shaped frame members for said bag movable toward and away from each other to open and close the same, and 45 rod means engaged in the hems and removably connected to the frame members.

6. A handbag cover having a pocket provided with an opening extending along the top and ends thereof and spaced from the bottom of the cover 50 to provide lower connecting end walls and side walls movable toward and away from each other, and elastic portions secured to and transverse to the end walls adjacent to the edges thereof to cause the end walls to snugly hug around a 55 foundation bag having frames and conceal the end portions of the frame thereof in open and closed positions of the foundation bag.

7. A handbag including a foundation bag, a frame permanently connected thereto, a cover, 60 said bag and cover having openings extending along the top and ends thereof, said cover having a pocket to receive the bag, the cover overlying the outside of the frame of the foundation bag, and means at the ends of the bag and cover 65 for releasably connecting the latter with the frame, said means including a rod means and a female element engageable with the rod means.
